CIRCUIT CONTROLLING MECHANISM

Application filed October 14, 1925. Serial No. 62,373.

This invention relates to circuit controlling mechanisms.

In electric make and break devices, commonly known as switches, there is a tendency to arcing between the switch contacts at the moment of break or make. The ordinary snap switch, now in general use, avoids a considerable amount of arcing by giving the moving contact a quick snap action into and out of engagement with the terminals. This is effected by interposing a spring between the switch button and contact arm, this spring being placed under tension by the rotation of the button until it reaches a given tension whereupon it snaps the contact arm from one position to another. Even in such switches, however, some arcing occurs, particularly in heavy duty switches, and this arcing is destructive to the switch mechanism.

It is an object of the present invention to provide a circuit controlling mechanism such that the customary type of snap button switch may be utilized in making and breaking circuits without any arcing.

With this general object, and others in view, the invention consists in the features, combinations, and details of construction and arrangements of parts which will first be described in connection with the accompanying drawings and then more particularly pointed out.

In the drawings—

Figure 1 is a perspective view of a circuit controlling mechanism constructed in accordance with the invention;

Figure 2 is a similar view showing the parts in different position;

Figure 3 is a schematic and diagrammatic view of the switch and wiring; and,

Figure 4 is a diagrammatic view of a modified construction.

As later appears in detail, the current to the energy-utilizing device, e. g. a resistor, is controlled by a switch of the contactor-terminal type and which may, for convenience, be designated a hand switch. Associated with this switch is a master switch that automatically causes a break in the main circuit during the makes and breaks of

the hand switch. While the hand switch may be of any desired construction, it may conveniently be a snap switch of standard type.

Referring to the drawings, Figs. 1-3 illustrate an embodiment of the invention in which the hand switch is a multiple switch of the type which gives three circuit arrangements and "off". This type of switch is commonly utilized in heating appliances, e. g. hot plates. By controlling individual branch circuits the switch gives high, medium and low heats and "off" and is known as a three heat switch. The particular switch here illustrated as an example comprises a spindle 21 on which is mounted a handle or operating button 22. Freely rotatable about the spindle is a contactor unit comprising two spiders hereinafter referred to. The contactor unit is rotated indirectly by the button and spindle through a spring device giving a snap action. To this end, mounted on the spindle to rotate therewith are two spaced housing plates 25, 26, connected by a bridge piece 27. Wound around the spindle, and enclosed by the plates, is a spring 29, its two ends extending radially outward beyond the rims of the housing plates. In normal position these ends straddle the bridge 27 which serves as a tensioning abutment. They also straddle a lug 30 rigidly connected with the contactor unit. When the button is actuated, the rotation of the spindle moves lug 27 against one end of the spring. This may be either end as the switch operates in either direction.

The other end of the spring bears against lug 30 but owing to the friction between the contactor and terminals this pressure is ineffective until the spring attains a given tension. The movement of the bridge 27, therefore, moves one spring end away from the other, thereby winding up the spring, this continuing until a given spring tension is attained. During this tensioning movement the contactor unit is stationary. Upon a given tension being attained the friction is overcome and the end of the spring which is pressing against lug 30

now rotates the contactor unit in the direction of spindle movement with a snap action, the extent of movement being limited by the new engagement of contactor 5 and terminals. The first spring end, during this operation, has been moved slightly further than the angular movement of lug 30. Consequently when the button is released there is a slight retrograde movement of the spindle unit until the forward spring end moves back to engagement with lug 30. The parts are now all displaced angularly but have the same relative position as before. In the switch here shown the 10 angle of displacement is 90°.

The contactor unit carries two contactor plates or spiders located in offset planes. The rear spider 33 has two contactor arms 34, 35 located 90° apart. Each contactor 20 arm is composed of a double spring arm adapted to grip the corresponding terminals between them. The front spider 36 has three contactor arms 37, 38, 39 located 90°, 90° and 180° apart, respectively. These 25 also are composed of spring arms to grip the terminals.

The switch has two sets of terminals located in planes to correspond with the contactor arms. The rear set comprises a top 30 terminal 40 and a left side terminal 41 located 90° apart. The front set comprises a bottom terminal 42, a right side terminal 43 and a left side terminal 44, the two latter each being located 90° apart from the 35 bottom terminal and 180° apart from each other. Left side terminal 41 of the rear set and left side terminal 44 of the front set have a common bus bar 45. Line wires 46, 47 connect with top rear terminal 40 and bottom front terminal 42, respectively.

While the energy-utilizing device may vary, the drawing shows a stove or hot-plate 15 heated by resistors 16, 17 enclosed in a housing 18 below the hot-plate, these 45 resistors being indicated diagrammatically in Fig. 3. A conductor 11 connects one end of resistor 16 with the top rear terminal 40. A conductor 12 connects one end of resistor 17 with bus bar 45, thereby connecting it with both left side terminals 41, 44. A conductor 13 connects the other ends of both resistors to right front terminal 43.

Fig. 3 shows, diagrammatically, the parts in "off" position. As terminal 42, connected with line wire 47, is disconnected, no current passes.

For low heat the contactor unit is rotated 90° counter-clockwise from "off" position. In this position contactor arms 37, 38 bridge terminals 44, 42, the other contactor arms being disconnected. This arrangement connects the two resistors 16, 17 in the circuit in series, the circuit being traced from line wire 47, through terminal 42, front contactor spider 36, terminal 44,

bus bar 45, conductor 12, resistor 17, resistor 16, conductor 11, and terminal 40 to line wire 46.

For high heat the contactor unit is moved 180° from low heat, or, in other words, 90° from "off" position clockwise. In this position, rear contactor arms 34, 35 bridge terminals 40, 41 and front contactor arms 37, 39 bridge terminals 43, 42, arm 38 being out of contact. This connects the resistors in circuit in parallel. The circuit is traced from line wire 47 through terminal 42, front contactor spider 36, and terminal 43 to conductor 13. From the latter the circuit splits, one branch being traced through resistor 16, conductor 11, and terminal 40 to line wire 46, the other traced through resistor 17, conductor 12, bus bar 45, terminal 41, rear contactor spider 33, and terminal 40 to line wire 46.

For medium heat, the contactor unit is moved to a position 180° from "off". In this position, front contactor arms 37, 38, 39 bridge terminals 42, 43, 44. Rear contactor arm 35 is in contact with terminal 40 but arm 34 is unconnected. In this position the resistor 16 is connected in the circuit. The circuit is traced from line wire 47 through terminal 42, front contactor spider 36, terminal 43, conductor 13, resistor 16, 95 conductor 11, and terminal 40 to line wire 46.

Except for the spindle extension herein-after referred to, the switch construction and wiring arrangement above described 100 are known in the art and are of more or less standard construction.

There is provided means for causing the circuit to be broken during the make or break of the switch contacts. This may be 105 accomplished by a master switch in the main circuit and operated by the actuation of the switch button. That is, it is operated to open the circuit during the delay in the switch action between the start of the button movement and the snap of the contactor unit; and to close the circuit again following the snap of the contactors. Although capable of various constructions, in that here shown as an example, connected in the main 110 circuit, e. g. in line wire 46, is a master switch in the form of a mercury tube switch 55. This latter comprises a tube having two depending recesses 56, 57 into which extend terminals 58, 59 connected in series in 115 the line wire 46. The tube contains a volume of mercury 54 capacititated to connect the two terminals 58, 59 when the tube is horizontal and to disconnect the terminals when the tube is tilted out of the horizontal. The tube 55 is mounted in a clip 60 secured in a cradle 61. In normal position (Fig. 1) the tube is horizontal and the mercury connects the two terminals, thus completing 120 the circuit through the tube. When, how- 130

ever, the tube is tipped to some such position as in Fig. 2, the mercury flows down into the lower end of the tube and there is a break between the terminals, whereby the 5 main circuit is broken.

The cradle is rocked to tilt the tube into "off" position and retilted to "on" position for each actuation of the hand switch. To this end, as here shown as an example, the 10 cradle 61 is rigidly mounted on an extension 62 of a U-shaped lever 63 pivoted on a horizontal pin 64. Below the base portion of the lever 63 is a cam 65 fixed on the extending end of the spindle 21 of the hand switch. 15 The cam here shown as an example is square shaped, the corners constituting high cam portion for wiping contact with the lever. In normal position, a flat or low portion of the cam is presented to the lever, the lever 20 being held to the cam by a spring 66. In this position (Fig. 1) the tube is horizontal. When the spindle rotates the cam, a corner of the cam wipes against the lever to actuate the same, thus tilting the tube to open circuit 25 position. In the particular construction shown the throw of the spindle during the delayed action is such as to wipe two cam corners against the lever. Thus an intermediate flat portion is presented which 30 allows the tube to retake horizontal position during the cycle but this may be disregarded. The parts are so arranged that the second corner of the cam has displaced the lever and tilted the mercury tube switch 35 just prior to the snap action of the hand switch. That is, at the time the switch contactors leave their terminals and engage another set, the tube is in circuit-breaking position (Fig. 2). As a result, when the 40 hand switch contacts are breaking and making, the main circuit is broken. As there is no load on the hand switch there can be no arcing and the mercury tube switch is of a non-arching type. 45 As above described, after the snap action of the hand switch, there is a slight retrograde movement of the spindle into its new normal position. Upon this retrograde movement the cam is displaced reversely to 50 present a flat portion to the lever. Consequently, as the cam high point withdraws, the lever returns to normal position and retilts the tube to horizontal, thus closing the main circuit again. 55

Since the action of the spindle is the same for each circuit-controlling movement of the hand switch, the main circuit is broken and closed again every time the hand switch is 60 operated, the break being prior to the break in the hand switch and the make being subsequent to the make in the hand switch. As above stated, the hand switch is operable in either direction and as cam 65 is symmetrical with respect to the spindle, its op-

eration is the same for either direction of spindle movement.

The invention may be embodied in a simple on-and-off switch. For example, the switch shown may be modified by removing the front contactor spider, and connecting the line wires to terminals 40, 41, any energy-utilizing device being placed in the line. With such modification the switch operates in the same way mechanically and 70 for each actuation of the button the mercury tube switch functions as described. 75

In the embodiment first described, the master switch is in a main circuit having a number of branch circuits controlled by a single compound switch. The invention in its entirety includes a master switch in a main circuit having a number of branch circuits controlled by individual switches, either simple or compound. For example, 80 the mercury tube switch may be placed in the main circuit of a stove having a plurality of hot-plates, each having a switch duplicating the switch first described or a simple switch. This may be accomplished by 85 providing a cam for each switch unit, the several cams lying in a straight line, and by extending the length of the lever to cover all the cams. Such a construction is indicated more or less diagrammatically in Fig. 90

4. As here shown as an example, a lever 71 is provided which is like lever 63 except that its base portion is longer. Below the lever 71 are three cams 72, 73, 74 each a duplicate of cam 65, mounted on the respective 100 spindles of three independent hand switches. For convenience of illustration simple on-and-off switches 75, 76, 77 and single resistors 78, 79, 80 are indicated, but it will be apparent that multiple switches and three-heat wirings like the unit first described 105 may be substituted. In the main circuit is a mercury tube switch 55 like that described and mounted as described to be tilted by the lever. Whenever any one of the 110 hand switches is actuated the corresponding cam operates the lever 71 to tilt the mercury tube switch in the manner described. Thus, for any actuation of any hand switch, there is no load on the hand switch during the 115 break or make of the contacts and so there can be no arcing. In this latter construction, since the main circuit is broken for each operation of any hand switch, it may happen that the main circuit is broken while 120 one branch circuit is closed for duty. Such a break, however, is so brief as to be inconsequential. It is obvious that each unit may have its own mercury tube switch if desired.

The operation of the device will be clear 125 from the above without further description.

With the constructions described the life of the hand switch is prolonged by avoiding the destructive effects of arcing, and the master switch, except for mechanical break- 130

age of the tube, is practically indestructible. Further, the prevention of arcing is effected in such a way as to enable standard type hand switches to be utilized.

5. What I claim is:

1. In a switch for controlling a circuit the combination of terminals, a movable contactor for contacting with said terminals, a rotatable spindle and a spring connection between the spindle and contactor for operating the latter with a delayed snap action upon rotation of the spindle, and means actuated by said spindle and operable during such delay for causing the circuit to be broken before such operation of the contactor and closed after such operation.
- 10 2. In a switch for controlling a circuit the combination of terminals, a movable contactor for contacting with said terminals, a rotatable spindle, and a spring connection between the spindle and contactor for operating the latter with a delayed snap action upon rotation of the spindle and for permitting a retrograde movement of the spindle following the movement of the contactor, and means actuated by said spindle for causing said circuit to be broken during said delay in the switch action and to be closed again during said retrograde movement of the spindle.
- 20 3. In a switch for controlling a circuit the combination of terminals, a movable contactor for contacting with said terminals, a rotatable spindle, and a spring connection between the spindle and contactor for operating the latter with a delayed snap action upon rotation of the spindle and for permitting a retrograde movement of the spindle following the movement of the contactor, a mercury tube switch in said circuit, and a connection between said mercury tube switch and the spindle for tilting the mercury tube switch into open circuit position during said delay and retilting it to closed
- 25 4. In a switch for controlling a circuit the combination of terminals, a movable contactor for contacting with said terminals, a rotatable spindle, and a spring connection between the spindle and contactor for operating the latter with a delayed snap action upon rotation of the spindle and for permitting a retrograde movement of the spindle following the movement of the contactor, a mercury tube switch in said circuit, and a connection between said mercury tube switch and the spindle for tilting the mercury tube switch into open circuit position during said delay and retilting it to closed
- 30 5. In a switch for controlling a circuit the combination of terminals, a movable contactor for contacting with said terminals, a rotatable spindle, and a spring connection between the spindle and contactor for operating the latter with a delayed snap action upon rotation of the spindle and for permitting a retrograde movement of the spindle following the movement of the contactor, a mercury tube switch in said circuit, and a connection between said mercury tube switch and the spindle for tilting the mercury tube switch into open circuit position during said delay and retilting it to closed
- 35 6. In a switch for controlling a circuit the combination of terminals, a movable contactor for contacting with said terminals, a rotatable spindle, and a spring connection between the spindle and contactor for operating the latter with a delayed snap action upon rotation of the spindle and for permitting a retrograde movement of the spindle following the movement of the contactor, a mercury tube switch in said circuit, and a connection between said mercury tube switch and the spindle for tilting the mercury tube switch into open circuit position during said delay and retilting it to closed
- 40 7. In a switch for controlling a circuit the combination of terminals, a movable contactor for contacting with said terminals, a rotatable spindle, and a spring connection between the spindle and contactor for operating the latter with a delayed snap action upon rotation of the spindle and for permitting a retrograde movement of the spindle following the movement of the contactor, a mercury tube switch in said circuit, and a connection between said mercury tube switch and the spindle for tilting the mercury tube switch into open circuit position during said delay and retilting it to closed
- 45 8. In a switch for controlling a circuit the combination of terminals, a movable contactor for contacting with said terminals, a rotatable spindle, and a spring connection between the spindle and contactor for operating the latter with a delayed snap action upon rotation of the spindle and for permitting a retrograde movement of the spindle following the movement of the contactor, a mercury tube switch in said circuit, and a connection between said mercury tube switch and the spindle for tilting the mercury tube switch into open circuit position during said delay and retilting it to closed

In testimony whereof, I have hereunto set my hand.

EDWARD A. MAU.
